AIR CONDITIONER

William D. Hess, Evansville, Ind., assignor to Servel, Inc., New York, N. Y., a corporation of Delaware

Application May 3, 1954, Serial No. 427,236

3 Claims. (Cl. 62—129)

The present invention relates to air conditioning and more particularly to improvements in the control for room air conditioners of the type illustrated and described in a copending application for United States Letters Patent of John H. Jennings, Serial No. 391,453 filed Nov. 12, 1953.

One of the objects of the present invention is to provide a room air conditioner with a single movable element for controlling operation of the refrigeration system and air circulating fans and the opening and closing of separate fresh air inlet and stale air exhaust dampers in a predetermined sequence.

Another object is to provide a room air conditioner of the type indicated having a rotatable element movable in either direction to control operation of the elements of the conditioner including the opening and closing of separate fresh and exhaust air dampers at particular angular positions.

Another object is to provide a single dial control for a room air conditioner having a shaft for operating control switches and cams for actuating separate fresh and exhaust air dampers in a coordinated sequence to cool and dehumidify the air, ventilate with or without cooling or exhaust stale air.

Still another object is to provide a control arrangement for a room air conditioner which is of simple and compact construction, economical to manufacture and reliable in operation.

These and other objects will become more apparent from the following description and drawings in which like reference characters denote like parts throughout the several views. It is to be expressly understood, however, that the drawings are for the purpose of illustration only and not a definition of the limits of the invention, reference being had for this purpose to the appended claims. In the drawing:

Fig. 1 is a sectional side view of a room air conditioner incorporating the novel features of the present invention and showing the single rotatable control element for actuating the control switches and fresh and exhaust air dampers at different angular positions;

Fig. 2 is a plan view showing the relationship of the elements of the control;

Fig. 3 is a plan view of the manually actuated dial of the control;

Fig. 4 is a sectional plan view taken on line 4—4 of Fig. 1 showing the separate levers and linkages for operating the fresh and stale air dampers, respectively;

Fig. 5 is a sectional view taken on line 5—5 of Fig. 4 showing the actuating levers mounted to rock on a common vertical axis and the cams on the shaft for actuating the levers independently of each other;

Fig. 6 is a transverse sectional view taken on line 6—6 of Fig. 1 showing the hinged mounting of the dampers and the torsion springs for yieldingly holding the dampers in closed position;

Fig. 7 is a sectional plan view taken on line 7—7 of Fig. 1 showing the housing extending rearwardly from

2

the fresh air inlet opening of the inner compartment to the side wall of the outer compartment;

Fig. 8 is a sectional view in side elevation showing a control arrangement of modified construction; and

Fig. 9 is a diagrammatic view of the control switches and electric circuits for starting and stopping operation of the compressor and fans.

For purposes of illustration, the present invention is shown applied to a window type room air conditioning unit adapted to be mounted between the sill and sash of a window or other opening in the wall of a room. It will be understood, however, that the present invention may be applied to other types of room air conditioners such as console and other types. As illustrated in Figs.

15 1 and 2, the room air conditioner comprises a base 10 mounting a heat receiving element 11 at one end and a heat rejecting element 12 at its opposite end. In the illustrated embodiment, the heat receiving element 11 constitutes the evaporator and the heat rejecting element

20 12 constitutes the condenser of a refrigeration system. An electrically driven compressor 13 is mounted on the base and suitably connected to the evaporator 11 and condenser 12 to provide a refrigeration system as well understood by those skilled in the art. A transverse wall 14 extends upwardly from the base 10 and cooperates with a weather casing 15 to provide an outer compartment 16 adapted to project outwardly from the room to be conditioned into the atmosphere. Side walls 17 and 18 project upwardly from the base forwardly of transverse wall 14 and a top wall 19 extends inwardly from the transverse wall to provide an inner compartment 20 adapted to project into the enclosure. An intermediate wall 21 extends between the side walls 17 and 18 to divide the inner compartment into a lower chamber 22 and an upper chamber 23. The lower and upper chambers 22 and 23 are open at the forward end of the compartment and a decorative casing 24 encloses the walls of the compartment and provides an air inlet opening 25 at the bottom and an air outlet opening 26 above the intermediate wall.

the evaporator. A housing 38 extends rearwardly and outwardly from the air inlet opening 35 into the outer compartment 16 and laterally to the side of the weather casing 15 and overlies louvered openings 28a in the latter outside the room to be conditioned. The stale air exhaust opening 36 is located in the transverse wall 14 at the rear of the upper chamber 23. The fresh air inlet opening 35 is adapted to be opened and closed by a damper 39 while the stale air exhaust opening is adapted to be opened and closed by a damper 40, see Figs. 4, 5 and 6. The dampers 39 and 40 are illustrated in the form of hinged doors with the damper 39 mounted to swing about a vertical axis on the hinges 41 and damper 40 mounted to swing about a horizontal axis on the hinges 42. Helical springs 43 and 44 operate between the casing and dampers to yieldingly hold the doors in closed position with respect to the openings 35 and 36. It will be noted that the fresh air inlet opening 35 communicates with the suction side of the fan 31 in chamber 22 while the stale air exhaust opening 36 is located in the upper chamber 23 at the outlet side of the fan so that the fan will tend to suck in fresh outside air or exhaust stale room air under pressure when the respective damper 39 or 40 is open.

A single control element 46 is provided for starting and stopping the compressor 13 and fan motor 34 in a particular sequence and operate dampers 39 and 40 in coordination with the operation of the compressor and fan to selectively cool and dehumidify the air in the room or add outside fresh air to the room with or without cooling or exhaust stale air from the room. The single control element 46 is illustrated in the form of a dial, see Figs. 1 and 3, conveniently located at the top of the decorative casing projecting into the room. The dial 46 is marked with suitable indicia and is adapted to be turned in either direction relative to an index mark 47 on the casing to select the desired operating condition. Dial 46 is mounted on and rigidly connected to the upper projecting end of a shaft 48 extending through a control box 49 and mounting cams 50 and 51 for operating the dampers 39 and 40.

The control box 49 has separate electric switches 52 and 53 therein connected to start and stop operation of the compressor 13 and fan motor 34 at different angular positions of the shaft. The switches 52 and 53 may take other forms but in the form illustrated diagrammatically in Fig. 9, the switches comprise movable contacts 52a and 53a and a plurality of angularly related fixed contacts 52b, 52c, 52d, 52e, 52f, and 52g and 53b, 53c, 53d, 53e, 53f, and 53g, respectively. The movable contact 52a of switch 52 is connected to one side L₁ of an electric service main and is adapted to energize and start the motor driven compressor 13 when the movable contact is in engagement with any of the fixed contacts 52c, 52d and 52e, and deenergize and stop the compressor when in engagement with fixed contacts 52f, 52g and 52b. The movable contact 53a is connected to the line L₁ and energizes the fan motor 34 to operate at high speed when in engagement with fixed contacts 53c, 53e, 53f and 53g, energize and operate the fan motor at low speed when in engagement with fixed contact 53d and deenergize and stop the fan motor when in engagement with fixed contact 53b. The movable contacts 52a and 53a rotate with the shaft 48 so as to engage the fixed contacts at different angular positions. The fixed contacts 52b to 52g and 53a to 53g are shown spaced at equal angular distances, but it will be understood that the actual spacing of the contacts corresponds to the positions marked on the dial 46, see Fig. 4.

The cams 50 and 51, as shown most clearly in Figs. 4 and 5, are located one above the other on the depending end of the vertical shaft 48 and have peripheral cam surfaces with lobes and dwells for opening and closing the dampers 39 and 40 through suitable linkages at different angular positions of the shaft related to the position

of the switch contacts 52a and 53a. The linkage for actuating the damper 40 comprises a bell crank lever 54 mounted to rock on a pin 55 supported by a suitable bracket, see Fig. 5. The lever is in the form of a sheet metal piece bent to provide a U-shaped fold through which the pivot pin 55 extends with the ends constituting the separate arms of the bell crank. A cam follower 57 at the end of one arm engages the periphery of the cam 50 and a pushrod 58 connects the end of the other arm of the bell crank to a lug on the damper 40. When the lobe 53a of cam 50 is moved relative to the follower 57 it rocks the lever 54 counterclockwise as viewed in Fig. 4 and operating through the pushrod 58, rocks the damper 40 on its hinges 42 to uncover the opening 36 in the transverse wall 14.

The linkage for operating the damper 39 comprises a lever 60 mounted to rock on the fixed pin 55 below the bell crank lever 54. One end of the lever has a cam follower 61 engaging the periphery of the cam 51 and the opposite end of the lever extends through a slot 62 in the transverse wall 14. A link bar 63 has one end pivotally connected to the rearward end of the lever 60 and its opposite end connected to an actuating arm 64 projecting rearwardly from the damper 39. As illustrated most clearly in Fig. 6, the actuating arm 64 is in the form of a rod having a rightangular bend 65 lying against the surface of the damper and clamped in position thereon by an angle bracket 66. The rod projects upwardly from the connecting bracket 66 through an arcuate slot 67 in housing 38 with its end projecting outwardly from the damper at an angle thereto and downwardly through an opening in the end of the bar link 63 to provide an articulated connection therewith. When the lobe 51a of cam 51 is moved relative to the follower 61 it rocks the lever 60 counterclockwise and operating through the bar link 63 and actuating arm 64 swings the damper 39 to uncover the fresh air inlet opening 35. One form of the invention having now been described in detail, the mode of operation is explained as follows:

For purposes of description let it be assumed that the air conditioning unit is mounted in a window or other wall opening with the decorative casing 24 projecting into the room and the weather casing 15 projecting outwardly from the room into the atmosphere. When the dial 46 is in the "Off" position illustrated in Fig. 3, the control switches 52 and 53 are open and the dampers 39 and 40 are closed and the cams are in the positions illustrated in Figs. 4 and 5. Thus, outside air is prevented from entering the room and room air is prevented from flowing outwardly to the atmosphere.

The dial 46 may be rotated in either direction to obtain the desired operating condition. By rotating the dial 46 clockwise from the position shown in Fig. 3, cooling may be obtained with or without the addition of fresh air and by rotating the dial counterclockwise, ventilation may be obtained with the addition of fresh air or the exhaust of stale air. For any particular operating condition desired the indicated condition on the dial is brought into register with the index mark on the casing. For example, if maximum cooling is desired without the introduction of outside fresh air or the exhaust of stale room air, the dial may be rotated clockwise as viewed in Fig. 3 to register the "Full" on position with the index mark 47 on the casing. Such rotation of the dial 46 is transmitted through the shaft 48 to simultaneously engage the movable contacts 52a and 53a with the fixed contacts 52c and 53c, see Fig. 9. A circuit is then completed from L₁ of the service main through contacts 52a and 52c to the electric motor for compressor unit 13. The circuit is completed from the compressor motor to the other side of the line L₂ of the service main. When the compressor is started it produces a refrigerating effect in the evaporator as well understood by those skilled in the art. Simultaneously with the energization of the circuit for operating compressor 13, a circuit is completed from L₁

through the switch contacts 53a and 53c to the high speed terminal of the electric fan motor 34. The circuit to the motor 34 is completed from a common conductor to the line L₂ as illustrated in Fig. 9. Motor 34 drives the rotor of the fan 31 at high speed to draw in room air through the air inlet opening 25 and through the evaporator 11 in the lower chamber 22 of the inner compartment 20. The air flowing in contact with the evaporator 11 is cooled and dehumidified and the fan discharges the air into the upper chamber 23 of the inner compartment 20 and back into the room through the outlet opening 26 in the decorative casing 24. Motor 34 also drives fan 27 at high speed which draws in outside air through the louvers 28 in the sides of the weather casing 15 and propels it through the housing 29 and condenser 12 back to the atmosphere through the outlet opening 30 at the rear of the casing to cool the condenser. The unit continues to operate in the manner described to circulate room air into contact with the cooling element or evaporator 11 of the refrigeration system to cool and dehumidify the air in the room at a maximum rate.

If it is desired to cool a mixture of room air and outside fresh air at a low fan speed for sleeping comfort, the dial 46 is rotated clockwise as viewed in Fig. 3 to register the "Nite" condition on the dial with the index mark 47 on the casing. During such rotation of the dial 46 and shaft 48, contact 52a of switch 52 is moved into engagement with fixed contact 52d to maintain the compressor in operation and the contact 53a of switch 53 is moved into engagement with fixed contact 53d to disconnect it from the high speed terminal and connect it to the low speed terminal of the fan motor 34, see Fig. 9. The lobe 51a of the cam 51 also actuates the lever 60 counterclockwise during rotation of shaft 48 as viewed in Fig. 4 to rock the damper or door 39 to the dotted position illustrated in Fig. 7. Outside fresh air is then drawn in through the louvers 28a in the weather casing 15 by fan 31 and through the housing 38 and passageway 37 to the front of the evaporator 11 where it mixes with room air entering the air inlet opening 25. The mixture of room air and outside fresh air is then drawn through the evaporator 11 and into fan 31. Thus, the unit operates at the "Nite" setting to add a portion of outside fresh air to the room air being circulated and operates the fan at low speed to reduce the noise which might interfere with sleeping.

When the dial 46 is rotated clockwise to the next "Fresh Air" operating position, the compressor 13 is maintained in operation by the engagement of contact 52a of switch 52 with contact 52e and the fan motor 34 is returned to high speed operation by the engagement of contact 53a of switch 53 with fixed contact 53e. The air conditioning unit then operates in the same way as explained with respect to the "Full" on position except that a portion of outside fresh air is added to the room air recirculated through the evaporator 11.

Rotation of dial 46 clockwise to the next operative position stops operation of the compressor 13 by the engagement of contact 52a of switch 52 with the open circuit fixed contact 52f but maintains the fan motor 34 in operation at high speed by the engagement of contact 53a of switch 53 with fixed contact 53f, see Fig. 9. The air conditioning unit then operates to recirculate room air and add a portion of outside fresh air to the room. Such a condition is desirable in the spring and fall when no cooling is necessary but the air in the room is stagnant or devitalized.

By rotating the dial 46 clockwise to the next "Exhaust" position, the air conditioning unit operates to exhaust stale air from the room without cooling or the addition of outside fresh air. Rotation of the dial 46 and shaft 48 causes the lobe 51a of cam 51 to move away from the follower 61 on the lever 60 so that spring 43, see Fig. 6, rocks damper 39 on its hinges 41 to close the fresh air inlet

opening 35. Simultaneously with the closing of the damper 39, the lobe 50a on cam 50 moves relative to the follower 57 to rock the bell crank 54 which acts through the pushrod 58 to rock the damper 40 on its hinges 42 to open position. Air in the room is then drawn into the lower chamber 22 of inner compartment 20 and is discharged by the fan 31 into the upper chamber 23. The combined action of the fans 31 and 27 operates to exhaust the room air outwardly through the exhaust opening 36 and propel it through the housing 29 and outlet opening 30 in the weather casing to the atmosphere. Thus, stale room air is exhausted from the room.

Rotation of the dial 46 and shaft 48 clockwise from the "Exhaust" position to the "Off" position causes the lobe 50a of cam 50 to move away from the cam follower 57 and the spring 44 rocks the damper 40 to its closed position. Simultaneously, the switches 52 and 53 are moved to their initial "Off" position to stop operation of the air conditioning unit. It will be obvious that the dial 46 may be turned counterclockwise to obtain any desired operating condition as well as being moved in a clockwise direction.

In Fig. 8 a modified construction is illustrated which is substantially identical with the construction illustrated in Figs. 1 to 7 except for the location of the dial 71. In the modified construction the shaft 48 does not extend through the decorative casing 24 but instead, mounts a gear 70. The dial 71 with suitable indicia thereon is mounted to rotate on a shaft 72 journaled in and depending from the top wall 19 of the inner compartment 20. The dial 71 is located below the top wall 19 and projects outwardly through a suitable slot 73 in the front of the decorative casing. Shaft 72 extends upwardly above the top wall 19 of the casing and mounts a gear 74. An intermediate gear 75 is mounted on a stub shaft 76 projecting upwardly from the top wall 19 and meshes with the gears 70 and 74 to transmit the rotation of the dial 70 to the shaft 48. The modified construction illustrated in Fig. 8 operates in exactly the same way as previously described with respect to the construction illustrated in Figs. 1 to 7.

It will now be observed that the present invention provides a room air conditioner for cooling and dehumidifying the air in a room and having separate dampers controlled by a single movable element to supply fresh outside air to or exhaust stale air from the room. It will also be observed that the present invention provides a rotatable control element movable in either direction to operate separate fresh and exhaust air dampers at different angular positions. It will also be observed that the present invention provides a single dial control having a shaft for operating control switches and cams to actuate separate fresh and exhaust air dampers in a coordinated sequence to either cool and dehumidify the air, ventilate with or without cooling, or exhaust stale air. It will still further be observed that the present invention provides a control arrangement for a room air conditioner which is of simple and compact construction, economical to manufacture and reliable in operation.

While two embodiments of the invention are herein illustrated and described, it will be understood that further changes may be made in the construction and arrangement of elements without departing from the spirit and scope of the invention. Therefore, without limitation in this respect, the invention is defined by the following claims.

1. A room air conditioner comprising a compartment having a cooling element therein, means for supplying a cooling medium to the cooling element comprising a compressor, a motor operated fan for circulating room air through the compartment and cooling element therein, an opening to the compartment at the inlet side of the fan and communicating with the atmosphere outside the room, a second opening from the compartment at the outlet side of the fan and communicating with the atmosphere out-

side the room, a damper for each opening, a lever connected to each damper, a switch box having switches for controlling operation of the compressor and fan motor, and a single control element comprising a rotatable shaft for actuating the switches in the switch box in a predetermined sequence and cams on the shaft for actuating the levers to coordinate the opening and closing of the dampers at different angular positions of the shaft with the actuation of the switches in the switch box.

2. A room air conditioner comprising a housing adapted to be mounted in an opening in the wall of a room, said housing having a transverse wall dividing the housing into an inner compartment projecting into the room and an outer compartment projecting outwardly from the room, a second wall in the inner compartment for dividing it into upper and lower chambers, a refrigeration system having a compressor, a heat receiving element in the inner compartment and a heat rejecting element in the outer compartment, a fan in each compartment for circulating room air through the inner compartment and heat receiving element and outside air through the outer compartment and heat rejecting element, a motor for operating said fans, said inner compartment fan having an inlet in the lower chamber and an outlet from the upper chamber, a fresh air inlet in a portion of the transverse wall at the side of the lower chamber, a second exhaust opening in the transverse wall from the upper chamber, a damper for each opening, a lever connected to each damper, a switch box having switches for controlling operation of the compressor and fan motor, a rotatable shaft for actuating the switches in the switch box in a predetermined sequence, and cams on the shaft for actuating the levers for opening and closing the dampers at different angular positions of the shaft.

3. A room air conditioner comprising a housing adapted
